UNITED STATES PATENT OFFICE.

CHARLES F. IKLÉ, OF NEW YORK, N. Y.

DESIGN FOR AN EMBROIDERED FABRIC.

Application filed March 28, 1923. Serial No. 5,623. Term of patent 31 years.

To all whom it may concern:

Be it known that I, CHARLES F. IKLÉ, a citizen of the United States of America, residing in the city of New York, in the county and State of New York, have invented a new, original, and ornamental Design for Embroidered Fabric, of which the following is a specification, reference being made to the accompanying drawing, forming part thereof.

The figure discloses a plan view of the fabric.

I claim:

The ornamental design for embroidered fabric as shown.

CHAS. F. IKLÉ.
